CONSOLE FOR A BOWLING SCORING DEVICE

Richard G. Reineman, Balboa, Calif., assignor to
The Brunswick Corporation

Filed Jan. 15, 1971, Ser. No. 106,938

Term of patent 14 years

Int. Cl. D21—02

U.S. Cl. D34—5

Fig. 1

Fig. 2

FIG. 1 is a perspective view of the console of my design taken from above and to the right of the front thereof.

FIG. 2 is a top view of the scorer console of my design.

FIG. 3 is a rear view of the scorer console of my design.

FIG. 4 is a perspective view of the scorer console of my design taken from the above right of the rear thereof.

FIG. 5 is a side view of the scorer console of my design.

I claim:

The ornamental design for a console for a bowling scoring device, substantially as shown and described.
